UNITED STATES PATENT OFFICE.

JAMES T. COWLEY, OF SYRACUSE, NEW YORK, ASSIGNOR TO THE LAMSON COMPANY, OF SYRACUSE, NEW YORK, A CORPORATION OF MASSACHUSETTS.

POWER-CONTROL APPARATUS.

Application filed April 8, 1925. Serial No. 21,721.

To all whom it may concern:

Be it known that I, JAMES T. COWLEY, a citizen of the United States of America, and resident of Syracuse, in the county of Onondaga and State of New York, have invented new and useful Improvements in Power-Control Apparatus, of which the following is a specification.

This invention pertains to power controllers for pneumatic despatch systems and relates more particularly to automatic controllers of the so-called minimum flow type of which the patent to Libby 968,576, August 20, 1910, furnishes an early example.

Controls of this type comprise essentially a valve, hereafter referred to as the "main" valve located between the transmission tube and an air exhauster or vacuum drum and which normally cuts off carrier propelling air flow through the tube when the tube is idle, although a relatively small volume of air, insufficient to propel a carrier, and known as the "minimum flow" is at all times permitted to flow through the transmission tube,—and a pneumatic, for example a piston or diaphragm, which responds either directly or indirectly to changes in pressure in the transmission tube due to the momentary cutting off or checking of the minimum flow incident to the insertion of a carrier in the tube and which, by such response, opens wide the main valve to permit carrier propelling air flow through the transmission tube.

In the form of apparatus described in the Libby patent, the period during which the valve remains open is determined solely by the operation of a timing device. The present invention is intended to improve the operation of devices of this general type by eliminating the timing device and in place thereof providing means which is responsive directly to the change in pressure in the transmission tube incident to discharge of the last carrier therefrom, thereby to initiate closure of the main controlling valve.

In the accompanying drawings a preferred embodiment of the invention is illustrated by way of example and in such drawings:

Fig. 1 is a diagrammatic elevation to small scale, partly in section, showing the

improved controller installed between one transmission tube of a pneumatic system and the exhauster header thereof;

Fig. 2 is a plan view of the controlling device to large scale;

Fig. 3 is a fragmentary vertical section, substantially on the line 3—3 of Fig. 2, showing the parts in normal position with the main valve closed, the transmission line being idle and no carrier being present in the tube;

Fig. 4 is a fragmentary section to smaller scale showing the interior construction of the lower part of the controlling apparatus;

Fig. 5 is a view similar to Fig. 3, but showing the parts in the positions which they occupy at the instant of full opening of the main valve;

Fig. 6 is a fragmentary section showing the relative positions of the primary and secondary auxiliary valves during the flight of the carrier through the tube;

Fig. 7 is a view similar to Fig. 6 showing the primary and secondary auxiliary valves at the instant after the last carrier has emerged from the transmission tube and before the main valve has closed;

Fig. 8 is a vertical section substantially on the line 8—8 of Fig. 2;

Fig. 9 is a vertical section substantially on the line 9—9 of Fig. 2; and

Fig. 10 is an elevation, partly in vertical section on the line 10—10 of Fig. 2.

Referring to the drawings and particularly to Fig. 1, the numeral 1 indicates a portion of a central station desk or other suitable support provided with the open despatch terminal 2 forming a part of the sending transmission tube 3 leading to an outlying station. The corresponding return transmission tube 4 is provided with the usual normally closed delivery terminal 5 and with the extension tube 6 which passes down through the top of the desk 1 and is connected with the power control apparatus designated generally by the numeral 7. A suction tube 8 leads from the power control apparatus to the usual suction drum or header 9 in which a vacuum or sub-atmospheric pressure is maintained by means of a suitable exhauster not shown. A continuous air passage or conduit is thus

provided extending from the terminal 2 of the transmission tube to the exhauster, that portion of the conduit provided by the tubes 3 and 4 constituting the transmission line.

- 5 Referring more particularly to Figs. 3 and 4 the improved power controller 7 which forms the immediate subject matter of the present invention comprises an elongate hollow casing 10 having an opening in its 10 side wall defined by a flange 11 for the reception of the end of the tube extension 6. The lower end of this casing is also furnished with an opening for the reception of the end of the suction tube 8.
- 15 The interior of the casing 10 (Fig. 4) is divided into an inlet chamber 13 communicating at all times with the transmission tube end an outlet chamber 14 communicating freely with the suction tube 8 by means 20 of a partition or septum 15. Preferably this partition is U-shaped, comprising the substantially parallel walls 17 and 18. These walls are furnished respectively with coaxial valve orifices providing communication 25 between the chambers 13 and 14. Normally these orifices are closed by the heads 19 and 20 respectively of a valve 21 of balanced type. While this form of valve is preferred the invention is not concerned 30 particularly with the character of the valve employed.

As herein shown the tubes 6 and 9 are connected by means of a small pipe 6^a (Fig. 4) which permits a constant flow of air of 35 small volume, known as the minimum flow, to be drawn through the transmission tube even when the main valve 21 is closed. While it is preferred to employ this small 40 pipe outside of the casing 10 it is contemplated that similar results may be obtained by providing a small passage through the septum 15 or alternatively by permitting leakage past the valve heads.

The upper wall 10^a of the casing 10 (Fig. 3) preferably comprises a removable section 22 for convenience in assembling the parts. This removable section or cover is furnished with a central boss 23 having a 50 guide passage for the stem 24 of the main valve 21. The upper wall 10^a of the casing is also extended laterally and upwardly to provide the saucer shaped lower member 10^b of the main motor casing. This bottom member 10^b terminates in a radial flange 25 forming a seat for the edge of a flexible diaphragm 26. The edge of this diaphragm is clamped between the flange 25 and a flange 27 at the margin of an upwardly concave cover member 28. The cover member 55 28 may be connected to the bottom member 10^b by means of bolts 28^a or other suitable fasteners.

The main motor casing comprising the members 28 and 10^b is divided by the diaphragm 26 into upper and lower chambers

29 and 30 respectively. The chamber 30 is always in free communication with the outer atmosphere through the port or ports 31. The central part of the diaphragm 26 is preferably clamped between stiffener plates 32 and 33. These plates and the diaphragm are provided with aligned apertures for the passage of the screw threaded upper end of the stem 24. A nut 34 clamps the diaphragm and the plates 32 and 33 together 75 and securely connects them to the stem.

An internally screw threaded sleeve or nut 35 engages the upper end of the stem 24 above the nut 34 and constitutes a socket for the lower end of a rod 37 forming an extension of the stem 24 and whose upper part passes through a guide opening in the upper end of a hollow gland 38 having screw threaded engagement with an opening in a boss 39 projecting from the top of the cover 28. A coiled spring 40 encircles the rod 37, its upper end being seated in the gland 38 and its lower end bearing against the sleeve 35. This spring tends to depress the diaphragm 26 and thus to close the main valve and retain the latter in its normal position. The tension of this spring may be varied by turning the gland 38.

A small bleeder opening 42 preferably controlled by an adjustable needle valve 43 permits atmospheric air slowly to leak into the chamber 29 of the main motor casing. The wall of the chamber 29 may, if desired, be provided with a second small opening 83 leading from the chamber 29 to the passage 76 hereinafter described and this opening 83 may also if desired be controlled by an adjustable needle valve 84.

The cover 28 of the main motor casing is provided with a boss 45 which furnishes a support for the base member 46 of the primary auxiliary pneumatic motor. The base 46 of this auxiliary motor is provided with a radial flange 57 forming a seat for the edge of a flexible diaphragm 58. The edge of this diaphragm is clamped between the flange 57 and a flange 59 forming the edge of a downwardly concave cover member 60. The diaphragm 58 divides the auxiliary motor casing into upper and lower chambers 61 and 62 respectively.

A boss 65 projects upwardly from the central part of the base member of the auxiliary motor casing and is provided with a guide passage for a sliding stem 66. The central part of the diaphragm 58 is clamped between stiffening plates 69 which have central openings for the reception of the screw threaded upper end of the stem 66, and a clamping nut 71 holds the several parts in assembled 125 relation. A rod 72, forming an extension of the stem 66, is connected at its lower end to the nut 71 and its upper part passes through a guide opening in the top of a gland 73 having screw threaded engagement with the 130

opening in a boss 74 projecting up from the top of the cover 60. A coiled spring 75 surrounds the rod 72 bearing at one end against the inner surface of the gland 73 and at its other end against the top of the nut 71. The tendency of this spring is to depress the diaphragm 58 and the tension of the spring may be varied by turning the gland 73.

A valve disk 79 is secured to the lower end of the stem 66. This valve disk cooperates with an annular seat 78 defining a valve orifice 77 connecting the chamber 38 of the main motor casing with a chamber 76^a in the boss 45 and which in turn opens into a passage 76 which leads to the chamber 13 and thus to the transmission tube. Normally the valve disk 79 is spaced from its seat 78 as shown in Fig. 3 so as to provide free communication between the chamber 29 and the transmission tube. The diaphragm 58 is furnished with a small vent opening 80 permitting the slow passage of air from one side to the other thereof.

The numeral 81 indicates generally a secondary auxiliary motor which is mounted upon a bracket 82 which may be integral with the base 46 of the primary motor or which may be supported in any other desired manner. This secondary motor comprises the bottom member 85 and the cover member 86 furnished with flanges 87 and 88 respectively at their edges between which the edge of a flexible diaphragm 89 is clamped. This diaphragm separates the interior of the secondary auxiliary motor casing into an upper chamber 90 and a lower chamber 91. The latter communicates at all times with the outer atmosphere by means of a port or ports 92.

The base member 85 of the secondary auxiliary motor casing is furnished with a central boss 93 having a guide passage for a sliding stem 94. The upper end of this stem is reduced in diameter and screw threaded and passes up through central openings in stiffener plates 95 disposed upon opposite sides of the diaphragm and which are clamped to the stem 94 by means of a nut 96. A rod 97 forming an extension of the stem 94 is connected at its lower end to the upper end of the stem 94 and its upper part passes through a guide opening in the top of a hollow gland 98 having screw threaded engagement with an opening in a boss 99 at the central part of a cover 86. A coiled spring 100 encircles the rod 97, bearing at its upper end against the gland 98 and at its lower end against the nut 96. The tension of this spring is varied by turning the gland 98 and the tendency of the spring is to depress the diaphragm 89.

The lower part or base member 85 of the secondary motor casing is furnished with an annular sleeve-like boss 101 concentric with the stem 94. The chamber 102 within this

boss 101 is normally open at the orifice 103 to the outer atmosphere. A pilot valve 104 is secured to the lower end of the stem 94 and when the diaphragm 89 is raised, this valve seats against the lower edge 101^a of 70 the boss 101, thus closing the orifice 103. A passage 105 extending through the bracket 82 leads from the chamber 102 to the lower chamber 62 of the primary auxiliary motor. 75

The upper chamber 90 of the secondary auxiliary motor communicates with the transmission tube by means of a passage which opens into the chamber 90 at the point 106. This passage extends upwardly into a boss 107 (Figs. 3 and 10) on the cover 86 of the secondary motor casing and then extends downwardly as indicated at 108 into the bracket 82 where it merges with a passage 109 extending along said bracket and into a boss 110 (Fig. 9) upon the base 46 80 of the primary auxiliary motor casing. The passage 109 is connected (see Fig. 8) with a radial passage 111 extending inwardly through the base member 46 of the primary motor casing and opening into the chamber 76^a at the point 112. Since the chamber 76^a is always in communication with the transmission tube the pressure in the upper chamber 90 of the secondary auxiliary motor casing is always substantially that of the transmission tube. 85

Referring to Figs. 9 and 10 a passage 113 extends upwardly from the passage 109 into a boss 114 projecting from the cover 60 of the primary auxiliary motor. This passage 113 communicates by means of a downwardly inclined passage 115 with the upper chamber 61 of the primary auxiliary motor. An adjustable needle valve 116 is provided for regulating the effective size of the passage 113. 100

The operation of the device is substantially as follows, it being assumed that when the transmission line is idle the parts of the control device occupy the positions shown in Fig. 3, the main valve being closed and the auxiliary valves 79 and 104 being open. It is also assumed that the spring 100 is stiffer than the spring 75 so that a greater degree of vacuum is necessary to close the valve 104 than is necessary to close the valve 79. 110

When a carrier is introduced into the transmission line either at the terminal 2 or at the outlying station the minimum flow of air normally entering the terminal 2 is cut off or substantially diminished with the result that the suction in the transmission tube and the chambers connected therewith is increased. The spring 37 of the main motor is so adjusted that when the carrier is introduced into the transmission tube and the suction thus increases the main diaphragm 26 will rise thereby opening the main valve 21. The diaphragms 58 and 89 of the auxiliary motors do not respond to 115 120 125 130

this initial increase in suction, but when the main valve opens the suction in the transmission line is still further increased and to a high degree, and the diaphragms 58 and 89 now respond to this suction to close their respective valves. Since the passage leading to the chamber 61 of the primary auxiliary motor is restricted by a proper setting of the needle valve 116, this motor is prevented from closing its valve prior to the full opening of the main valve or prior to the closure of the valve 104. As soon as the valve 79 closes, air which constantly leaks in through the passage 42 begins gradually to build up pressure upon the upper side of the diaphragm 26 and thus eventually would allow the main valve to close. Before such action can take place the valve 104 is closed, as already pointed out, thus cutting off the chamber 62 of the primary auxiliary motor from the atmosphere. As the upper chamber 61 of this motor communicates with the transmission tube, and as the lower chamber communicates with the upper chamber by means of the passage 80 the pressures upon the opposite side of the diaphragm 58 tend to equalize and the spring 75 again opens the valve 79. This action takes place very rapidly so that the chamber 29 of the main motor is again placed in full communication with the transmission tube before the main valve can close.

The parts now remain in this position until the last carrier emerges from the transmission tube. When this occurs a slight decrease in suction in the transmission tube is produced since the frictional drag and inertia of the carrier are removed. The spring 100 is so adjusted that this slight change in pressure in the transmission tube is sufficient to allow the diaphragm 89 to drop, thus opening the valve 104. When the valve 104 opens as indicated in Fig. 7, communication is established between the lower chamber 62 of the primary auxiliary motor and the outer atmosphere, and the diaphragm 58 being under suction immediately rises and again closes the valve 79 as indicated in Fig. 7. Since the chamber 29 of the main motor is now cut off from the transmission tube the pressure slowly builds up in the chamber 29 through the port 42 until the spring 40 is able to depress the diaphragm 26 and thus to close the main valve. The rate of pressure equalization in the chamber 29 may be very nicely adjusted by the two needle valves 43 and 84 so that the interval between the delivery of the carrier from the tube and the closure of the main valve may be determined with great accuracy.

When the main valve closes, the suction in the transmission tube immediately returns substantially to normal, the original pressure in the chamber 61 of the primary auxiliary motor is gradually restored, and the spring

75 again opens the valve 79. The parts are all thus returned to their initial position ready for a repetition of the operation.

While I have shown a preferred arrangement of parts I contemplate that various changes and modifications may be made both in shape, size and relative arrangement of parts, and also the substitution of equivalents for the elements herein disclosed, and regard all such changes and substitutions as within the spirit of the invention.

I claim:

1. Power control apparatus for a pneumatic despatch system having a transmission tube comprising a main valve for controlling carrier propelling air flow through the tube, a main pneumatic motor for operating the main valve, said motor having a pressure actuated element normally exposed to the pressure obtaining in the transmission tube, controlling means responsive to a predetermined pressure in the transmission tube for cutting off communication between the main motor and the transmission tube, and means to terminate response of said controlling means to said predetermined pressure.

2. Pneumatic despatch apparatus having a transmission tube, an exhauster connected therewith, and a main valve for controlling the flow of air through the transmission tube, a minimum flow of air through the tube being permitted when the valve is in closed position, and a pneumatic motor for operating the main valve, said motor having a pressure sensitive element normally exposed to the pressure obtaining in the transmission tube, an auxiliary pneumatic motor having a pressure sensitive element moving from normal position upon the occurrence of a predetermined pressure in the transmission tube thereby to cut off communication between the tube and main motor, and means to terminate response of the auxiliary motor to such predetermined pressure whereby to permit its pressure sensitive element to return to normal position.

3. Power control apparatus for a pneumatic despatch system having a transmission tube comprising a main valve for controlling carrier propelling air flow through the tube, a main pneumatic motor for operating the main valve, said motor having a pressure actuated element responsive to pressure change in the transmission tube, an auxiliary motor having a pressure sensitive element exposed on one side to transmission tube pressure and normally exposed upon its other side to atmospheric pressure, said element responding to a predetermined pressure in the transmission tube to cut off communication between the main motor and the transmission tube, and means for cutting off the auxiliary motor from atmospheric pressure.

4. Pneumatic despatch apparatus having a

transmission tube, an exhauster connected therewith, a main valve for controlling the flow of air through the transmission tube, a minimum flow of air through the tube being permitted when the valve is in closed position, and a pneumatic motor for operating the main valve, said motor having a pressure sensitive element responsive to pressure change in the transmission tube 5 incident to insertion of a carrier into the transmission tube thereby to open wide the main valve, a controlling valve, an auxiliary pneumatic responsive to pressure drop in the transmission line incident to introduction 10 of a carrier thereby temporarily to close the controlling valve and cut off communication between the main motor and tube, and a second auxiliary pneumatic operative to open said controlling valve again and to hold it open so long as a carrier remains in the tube.

5. Power control apparatus for a pneumatic despatch system having a transmission tube comprising a main valve for controlling carrier propelling air flow through the tube, a main pneumatic motor for operating the main valve, said motor having a pressure actuated element responsive to pressure change in the transmission tube, an auxiliary 25 motor comprising a casing having chambers separated by a flexible diaphragm, one of said chambers communicating by means of a restricted passage with the transmission tube and the other communicating by means of a normally open passage with the outer atmosphere, a valve actuatable by said diaphragm to cut off communication between the main motor and the transmission tube, a pilot valve for closing said normally open passage, and means responsive to delivery 30 of a carrier from the transmission tube to close said pilot valve.

6. Pneumatic despatch apparatus having a transmission tube, an exhauster connected therewith, and a main valve for controlling the flow of air through the transmission tube, a minimum flow of air through the tube being permitted when the valve is in closed position, and a pneumatic motor for operating the main valve, said motor having a pressure sensitive element responsive to pressure change in the transmission tube, an auxiliary motor comprising a casing having chambers separated by a flexible diaphragm, one of said chambers communicating by means of a passage with the transmission tube, adjustable means for varying the effective size of said passage, a normally open passage leading from the other of said chambers to the outer atmosphere, an auxiliary valve actuatable by the diaphragm to cut off communication between the main motor and the transmission tube, a pilot valve for closing said normally open passage, and a pneumatic for operating the pilot valve.

7. Pneumatic despatch apparatus having a transmission tube, an exhauster connected therewith, and a main valve for controlling the flow of air through the transmission tube, a minimum flow of air through the tube being permitted when the valve is in closed position, and a pneumatic motor for operating the main valve, said motor having a pressure sensitive element responsive to pressure change in the transmission tube, an auxiliary motor comprising a casing having chambers separated by a pressure sensitive element, one chamber communicating with the transmission tube and the other communicating by means of a normally open passage with the atmosphere, said sensitive element responding to a predetermined pressure in the tube to cut off communication between the tube and the main motor, and a valve for closing the passage leading from the auxiliary motor to the atmosphere.

8. Power control apparatus for a pneumatic despatch system having a transmission tube comprising a main valve for controlling carrier propelling air flow through the tube, a main pneumatic motor for operating the main valve, said motor having a pressure actuated element responsive to pressure change in the transmission tube, an auxiliary motor having a diaphragm exposed on one side at all times to transmission line pressure and exposed on its other side, by means of a normally open passage, to the outer atmosphere, there being an opening of small capacity to permit air to pass slowly from one side of the diaphragm to the other, an auxiliary valve connected to the diaphragm and actuatable thereby to close communication between the main motor and the transmission tube, and a valve for closing said normally open passage.

9. Pneumatic despatch apparatus having a transmission tube, an exhauster connected therewith, and a main valve for controlling the flow of air through the transmission tube, a minimum flow of air through the tube being permitted when the valve is in closed position, and a pneumatic motor for operating the main valve, said motor having a pressure sensitive element responsive to pressure change in the transmission tube, an auxiliary pneumatic for controlling the action of the main motor, and a second auxiliary pneumatic controlling the action of the first auxiliary pneumatic.

10. Power control apparatus for a pneumatic despatch system having a transmission tube comprising a main valve for controlling carrier propelling air flow through the tube, a main pneumatic motor for operating the main valve, said motor having a pressure actuated element responsive to pressure change in the transmission tube, a controlling valve for the main motor, an auxiliary pneumatic for actuating the con-

- trolling valve, a pilot valve for determining operation of the auxiliary pneumatic, and a pressure actuated pneumatic for actuating the pilot valve.
- 5 11. Pneumatic despatch apparatus having a transmission tube, an exhauster connected therewith, and a main valve for controlling the flow of air through the transmission tube, a minimum flow of air through the tube being permitted when the valve is in closed position, and a pneumatic motor for operating the main valve, said motor having a pressure sensitive element responsive to pressure change in the transmission tube,
- 10 15 an auxiliary motor having a diaphragm exposed on one side to transmission tube pressure and normally exposed on its other side, through a normally open passage, to atmospheric pressure, an auxiliary valve for controlling the main motor, means connecting the auxiliary valve to the diaphragm, a pilot valve for closing said normally open passage, and a pneumatic for actuating the pilot valve, said pneumatic being exposed on one side to transmission tube pressure and on its other side to atmospheric pressure.
12. Power control apparatus for a pneumatic despatch system having a transmission tube comprising a main valve for controlling carrier propelling air flow through the tube, a main pneumatic motor for operating the main valve, said motor having a pressure actuated element responsive to pressure change in the transmission tube, an auxiliary pneumatic for controlling the action of the main motor, and a second auxiliary pneumatic controlling the action of the first auxiliary pneumatic, each of said pneumatics being exposed at one side to transmission tube pressure, one of said pneumatics responding more quickly to predetermined pressure change in the transmission tube than the other.
13. Pneumatic despatch apparatus having a transmission tube, an exhauster connected therewith, and a main valve for controlling the flow of air through the transmission tube, a minimum flow of air through the tube being permitted when the valve is in closed position, and a pneumatic motor for operating the main valve, said motor having a pressure sensitive element responsive to pressure change in the transmission tube, a primary auxiliary pneumatic for controlling the action of the main motor, a secondary auxiliary pneumatic controlling the first auxiliary pneumatic, each of said pneumatics being exposed on one side to transmission tube pressure, both of said pneumatics being responsive to the drop in pressure in the transmission tube incident to opening of the main valve, the secondary pneumatic only being responsive to the slight increase in pressure in the tube incident to delivery of the last carrier therefrom.
14. Pneumatic despatch apparatus having a transmission tube, an exhauster connected therewith, and a main valve for controlling carrier propelling air flow through the tube, a minimum flow of air through the tube being permitted when the main valve is closed, a main pneumatic motor for actuating the main valve, said motor comprising a casing having chambers separated by a flexible diaphragm, one of said chambers always being open to atmospheric pressure and the other communicating by means of a normally open passage with the transmission tube, a controlling valve for closing said passage, means connecting the diaphragm of the main motor to the main valve, a primary auxiliary pneumatic for closing the controlling valve, and a secondary auxiliary pneumatic for determining the pressure acting upon one side of the primary auxiliary pneumatic.
15. Pneumatic despatch apparatus having a transmission tube, an exhauster connected therewith, and a main valve for controlling carrier propelling air flow through the tube, a minimum flow of air through the tube being permitted when the main valve is closed, a main pneumatic motor for actuating the main valve, said motor comprising a casing having chambers separated by a flexible diaphragm, one of said chambers being always open to atmospheric pressure and the other communicating by means of a normally open passage with the transmission tube, a controlling valve for closing said passage, means connecting the diaphragm of the main motor to the main valve, means for closing the controlling valve, and an auxiliary pneumatic motor for controlling said valve closing means, said auxiliary motor comprising a casing having chambers separated by a flexible diaphragm, one of said chambers being always open to the atmosphere and the other communicating with the transmission tube.
16. Pneumatic despatch apparatus having a transmission tube, an exhauster connected therewith, and a main valve for controlling carrier propelling air flow through the tube, a minimum flow of air through the tube being permitted when the main valve is closed, a main pneumatic motor for actuating the main valve, said motor comprising a casing having chambers separated by a flexible diaphragm, one of said chambers being always open to atmospheric pressure and the other communicating by means of a normally open passage with the transmission tube, a controlling valve for closing said passage, means connecting the diaphragm of the main motor to the main valve, a primary auxiliary motor comprising a casing having chambers separated by a flexible diaphragm, one of said chambers communicating with the transmission tube and the other normally communicating with the transmission tube.

cating with the outer atmosphere by means of a normally open passage, means connecting the flexible diaphragm of the primary auxiliary motor with the controlling valve 5 of the main motor, a pilot valve for closing said last named open passage, and a secondary auxiliary motor for actuating said pilot valve, said secondary motor comprising a casing having chambers separated by a

flexible diaphragm, one of said chambers 10 communicating with the transmission tube and the other being open at all times to the outer atmosphere, and means connecting the diaphragm of the secondary motor to the pilot valve.

Signed by me at Syracuse, New York, this twenty-fifth day of March, 1925.

JAMES T. COWLEY.
